GOLF CLUB

Milton B. Reach, Springfield, Mass.

Application May 17, 1941, Serial No. 393,903

16 Claims. (CL. 273—77)

This invention relates to golf club irons having a toe to heel length several times that of the face to back width, and particularly to multi-piece golf irons.

Reference is made to a copending application by the same inventor, Serial No. 322,885 filed March 8, 1940, which discloses a golf iron having a hardened bottom plate, and having a lie-controlling bottom plate. The present invention embodies certain novel simplifications and improvements over said application Serial No. 322,885.

Prior to the development of the clubs described in said copending application, golf irons were generally made in one piece of steel forgings. For economy, and to have an ideal striking face, such one piece irons were usually made of soft steel or mild steel. An important disadvantage of the one piece soft steel golf iron is that a relatively short period of normal play causes the bottom portion of the iron to become nicked and scratched by rocks. Such nicks and scratches sometimes mar and harm the golf ball. Efforts to harden the entire blade have resulted in destroying the "sweet" feel of the club and/or making the entire club too brittle and/or too expensive for profitable manufacture.

It is an important object of the present invention to provide a golf club having a bottom surface with a high resistance to abrasion, wear and adverse nicking, said club also having a "sweet" feel even better than that of a conventional golf iron.

It is another object of the present invention to provide a hard bottom or wear plate for irons which, although structurally simple and inexpensively manufactured, is very sturdily held in place.

Another object is to supplement the holding screws for a bottom plate in such a manner that, even though the screws loosen, the plate will still be maintained against the main body of the head.

Special problems are involved in trying to provide a hard plate at the bottom of a body portion of a golf iron head because such heads are not thick and do not provide very much thickness, area, and/or volume for holding means.

It is therefore an important object of the present invention to provide a head structure for irons to which a bottom plate may be advantageously secured.

Further important aims of the present invention are to devise a golf club embodying the various objectives just set forth and also: pos-

sessing advantageous weighting means by which a tendency to hook or slice can be controlled or corrected; capable of being easily modified to possess whatever lie is deemed desirable; having a low manufacturing cost; having a multi-piece blade which is easily assembled and disassembled; having securing means with its axis substantially within the plane bisecting the mass of the blade; and having weighting means with its axis substantially within the plane bisecting the mass of the blade.

Particular attention is directed to the fact that an important feature of several forms of the present invention is the provision of interengaging means, such as a dovetail joint, preferably an arcuately disengageable dovetail joint, to prevent the plate from falling from the body of the head even though holding screws loosen. Such interengaging means may be a V-slot, sloping wall slot, T-slot, or other type of joints of the class of joints characterized by a channel with depthwise diverging sidewalls and portions engaging with said depthwise diverging sidewalls.

It should be especially noticed that certain forms of the present invention include the novel feature of spline means such as a floating rectangular block within adjoining recesses to prevent certain relative movement between the bottom plate and the body of the blade.

In the drawings:

Figure 1 represents a front view of a preferred form of the present invention.

Fig. 2 is a bottom view of the iron of Fig. 1.

Fig. 3 is a cross-sectional view of Fig. 1, taken on the line 3—3 of Fig. 1.

Fig. 4 is a front view without the plate.

Fig. 5 is a side view of the plate showing its upper surfaces in a horizontal plane.

Fig. 6 is a top view of the plate shown in Fig. 5, as indicated by the line 6—6 of Fig. 3.

Figs. 7 and 8 are cross-sectional views of Fig. 1, taken on the lines 7—7 and 8—8 respectively of Fig. 1.

Figs. 9 through 11 represent the main central planes of irons of divers lofts.

Figs. 12 through 16 are views of a modified form of the present invention. Fig. 12 is a front view of the body without the plate. Fig. 13 is a side view of the plate showing its upper surfaces in a horizontal plane. Fig. 14 is a top view of the plate showing its upper surfaces in a horizontal plane. Fig. 15 is a perspective view of the block of the modified form of the invention. Fig. 16 is a cross-sectional view of the modified form of the invention shown in Figs. 12 through 15.

Fig. 17 is a front view of a simple alternative form of the present invention.

Fig. 18 is a cross-sectional view of Fig. 17 on the line 18—18 of Fig. 17.

Fig. 19 is a diagrammatic representation to show that the lie of the clubs of the present invention can be easily modified.

Throughout the specification the term "length of the club blade" refers to the heel-to-toe or longitudinal dimension; "width" refers to the face-to-back or lateral dimension; "height" refers to the bottom-to-top or vertical dimension; and "bottom" refers to the surface which in normal play is nearest the ground at the moment of impact of the ball and club.

Before describing the present improvements and mode of operation thereof in detail it should be understood that the invention is not limited to the details of construction and arrangement of parts shown in the accompanying drawings, which are merely illustrative of the present preferred embodiments, since the invention is capable of other embodiments, and the phraseology employed is for the purpose of description and not of limitation.

Referring now in detail to the figures, and particularly to the simplest form of the invention as shown in Figs. 17 and 18, there is provided a blade 30 consisting essentially of a body 31 and a bottom plate 32. The blade 30 is connected to a conventional shaft, not shown, by suitable means, usually including a hosel 33. In the form shown in the drawings, the blade and hosel form a head 34 having suitable design features to increase sales appeal. A geometric plane 35 is shown in Fig. 18. It should be particularly noted that the geometric plane 35 bisects the mass of the blade and is somewhat, but ordinarily not entirely, parallel to the striking face of the blade. The geometric plane 35 which divides the blade into forward and rear portions of substantially equal mass is sometimes designated hereinafter as the main central plane.

It should be particularly noted that the body 31 and plate 32 are united by simple and advantageous spline means 36, best shown in Fig. 18. A recess 37 having sidewalls 38 in the body adjoins a recess 39 having sidewalls 40 in the plate. Within both of the recesses is a block 41 adapted to snugly engage sidewalls 38 and 40 of the recesses 37 and 39 of the body and plate respectively. The block 41 and the recesses 37 and 39 therefore may be as long as the plate 32 and adjacent section of the body 31, or may be one inch long or some other preferred length. A screw 42 having shoulders 43 engaging with the block is adapted to pass through the plate, block and into threaded engagement with the body. The plate is thus secured to the body by a single screw and the spline means. More than one screw may be used, if preferred. The block is clamped to the body by the screw so that separation, vibration and chatter are prevented.

Particular attention is directed to the fact that the axis of the screw is disposed substantially within the main central plane 35. Because the axis of the screw is within the main central plane, the manufacturing difficulties incident to the use of securing means for uniting the bottom plate to the body of the blade are minimized. The likelihood of drilling through the rear surface of the body is eliminated by disposing the axis in the main central plane. It should especially be noted that the likelihood of drilling through the striking face of the body is eliminated. If the

screw protruded into the striking face, a golf ball might be marred or damaged when struck. Moreover, even if the screw did not protrude when the club head was initially manufactured, if there were thin sections incident to the disposing of the axis other than substantially in the main central plane, those thin sections would substantially weaken the body and might cause it to break after a short period of normal use.

Moreover, by disposing the screw 42 in the main central plane, the center of gravity of the blade 30 is not modified, and other important advantages are achieved.

Attention is also called to the fact that the plate 32 is preferably of harder metal than the body 31, and that the plate determines the lie of the club. To change the lie of the club head 34, it is only necessary to replace the plate with another having different lie characteristics (e. g. have the plate 32 thick at heel section and evenly tapered to be thin at toe section, for an upright lie condition; and vice versa, have the plate thick at the toe section and evenly tapered to a thin heel section for a low lie condition).

In Figs. 12-16 there is shown an alternative form of the invention. A golf club head 44 includes a blade 45 consisting essentially of a body 46 and a bottom plate 47. It should be noted that interengaging means 48 are provided to better secure the plate to the body. The interengaging means includes a channel 49 preferably in the body, said channel having depthwise diverging sidewalls 50 abutting against downwardly converging portions 51 on the interengaging member to form a dovetail joint which, as explained hereinafter, is preferably an arcuately disengageable dovetail joint. T-slot joints, V-slot joints, and other joints adapted to prevent the separation of the plate from the body are also intended to be within the scope of the term dovetail joint, and within the scope of the phrase relating to depthwise diverging sidewalls. The term downwardly converging is meant to define whatever shape is necessary for cooperating with the shape of the depthwise diverging sidewalls, whether simple sloping, T-shaped, V-shaped or otherwise.

Preferably but not necessarily the dovetail joint may be arcuately disengageable. As shown in Fig. 14, the plate 47 has curved portions 52 at the ends. As shown in Fig. 16, a screw 53 is threaded into the plate. The screw is provided with a tip 53' entering a suitable bore in body 46 to act as pivoting means about which the plate moves arcuately. Attention is directed to the fact that the axis of the screw is preferably disposed substantially in the main central plane of the blade 45, and that the bottom surface of the body and the top surface of the bottom plate are thereby in a plane substantially at right angles to the main central plane. A recess 54 in the body and a recess 55 in the plate are adapted to receive a block 56 which cooperates with the screw to function as spline means preventing relative arcuate movement. The recess 55 in the plate is of sufficient depth to fully contain the block, so that the plate may be pivoted into place, and thereafter the block may be moved upwardly by shoulder 57 on the screw 53. The shoulder clamps the block against the body to prevent vibration and maintains the block in the locking position.

It should be particularly noted that in assembling the club head 44 of Figs. 12-16, the block 56 is dropped into the recess 55 in the plate 47 which recess fully contains the block. The screw 53 is then passed through the plate and block so that

the tip 53' enters the bore in the body 48 while the plate is substantially at right angles with most of the mass of the plate away from the body. The plate is then arcuately swung about the screw as a pivot, and the downwardly converging portions 54 of the plate are brought into engagement with the depthwise diverging sidewalls 55 of the channel 48 in the body. The dovetail joint thus formed prevents the plate from dropping from the body, and prevents all relative movement between the plate and body other than arcuate movement. When the single screw 53 is further tightened, the block 56 is raised until it is partly within the recess 54 in the body, while still remaining partly within the recess 55 of the plate, thereby preventing any arcuate movement between the plate and the body. As the bolt is further tightened, the block is clamped against the body to lock it in place and to prevent vibration.

In that form of the invention shown particularly in Figs. 1-8, a golf club head 58 includes a blade 59 consisting essentially of a metal body 60 and a bottom plate 61. Preferably, in the body is a channel 62 having depthwise diverging sidewalls 63 abutting against downwardly converging portions 64 of the interengaging member to form a dovetail joint. As explained hereinabove, depthwise diverging sidewalls and downwardly converging portions include T-slot formations, V-slot formations, and other cooperating surfaces adapted to prevent the plate from dropping out of the body. The dovetail joint is preferably arcuately disengageable.

A pivot stud 65 integral with or secured to the bottom plate 61 is adapted to fit in a socket 66 in the body 60 and to constitute pivoting means about which the bottom plate can arcuately move. The relative arcuate movement engages and disengages the dovetail joint. Screws 67 passing through the plate and into threaded engagement with the body prevent arcuate movement of the plate relative to the body and maintains the body and plate engaged in said dovetail joint. As shown in Fig. 8, the screws are preferably disposed so that their axes are substantially in a main central plane 68 bisecting the mass of the blade 59. The manufacturing difficulties of drilling the body are minimized by disposing the axes of the screws in the main central plane, inasmuch as the likelihood of drilling through the body is substantially eliminated. Moreover, the center of gravity of the blade is not affected by the screws when thus disposed. The pivot stud 65 is also positioned with its axis substantially in the main central plane. In Figs. 9-11 the effect of loft upon the main central plane is illustrated. Especially in clubs having faces substantially angularly distant from the vertical (e. g. Fig. 9), advantages accrue from having the axis of the pivot stud substantially in the main central plane. The tendency for the impact with the ball to arcuately swing the bottom plate relative to the body is substantially lessened by disposing the pivot stud in the main central plane and many other advantages result from this structural arrangement.

It should be noted that the blade 59 may be provided with a plurality of weight-receiving recesses 69 disposed along a line from heel to toe, each recess preferably having its axis substantially in the main central plane 68 and in the body 60. Weights 70 may be placed in a recess near the heel or toe to compensate for a tendency to slice or a tendency to hook. Weights may be placed in the outer recesses to increase the moment of inertia of the club about a vertical axis,

or weights may be placed in the inner recesses to minimize the moment of inertia of a weighted club. Moreover, the weights can also be used in the center recesses, or in all of the recesses, to control the weight of the club head, so that it will have the desired feel when used in play. The weights may be in threaded engagement with the body as shown in Fig. 7.

Variations and modifications may be made within the scope of this invention and portions of the improvements may be used without others.

Having thus described the invention, what is claimed as new is:

1. In a head for a golf iron the combination of a metal body having a channel laterally across the bottom thereof defined by arcuate and depthwise diverging sidewalls; a bottom plate; pivoting means associating the plate in said channel of the body for relative arcuate movement including arcuate and downwardly converging portions on said bottom plate engaging with said diverging walls; said pivoting means preventing other than arcuate movement between the plate and body; and securing means adapted to prevent said arcuate movement.
2. In a head for a golf iron the combination of a metal body having a channel laterally across the bottom thereof defined by arcuate and depthwise diverging sidewalls; a lie-controlling bottom plate, said body and bottom plate forming a blade having a main central plane; pivoting means associating in the plate in said channel and the body for relative arcuate movement, the axis of said pivoting means being substantially within said main central plane; arcuate and downwardly converging portions on said bottom plate engaging with said diverging sidewalls to prevent other than arcuate movement between the plate and body; and securing means adapted to prevent said arcuate movement.
3. In a head for a golf iron the combination of a metal body having a channel laterally across the bottom thereof defined by arcuate and depthwise diverging sidewalls, said body having a plurality of weight-receiving recesses extending from said channel; a lie-controlling bottom plate, said body and bottom plate forming a blade having a main central plane; weights having their axes substantially in said main central plane in said recess; a pivot stud having its axis substantially within said main central plane; said pivot stud associating the plate in said channel of the body for relative arcuate movement; arcuately shaped and downwardly converging portions on said bottom plate engaging with said diverging walls to prevent other than arcuate movement between the plate and body; and securing means adapted to prevent said arcuate movement.
4. In a head for a golf iron the combination of a metal body having a toe to heel length several times the face to back width, said body having a channel laterally across the bottom thereof defined by arcuate and depthwise diverging sidewalls; a bottom plate with curved ends; pivoting means associating the plate in said channel of the body for relatively arcuate movement including arcuate and downwardly converging portions on said bottom plate engaging with said diverging walls, said pivoting means preventing other than arcuate movement between the plate and body; and securing means adapted to prevent said arcuate movement.
5. In a head for a golf iron the combination of a metal body having a channel laterally across the bottom thereof defined by arcuate and depthwise diverging sidewalls, a plurality of weight-

receiving recesses, a toe to heel length several times the face to back width; a bottom plate of harder metal than the body, said body and plate forming a blade having a main central plane; weights in said recesses and having their axes substantially in said main central plane; a pivot stud on the bottom plate and engaging with said body for relative arcuate movement, the axis of said pivot stud being substantially in the main central plane; arcuately shaped and downwardly converging portions on said bottom plate engaging with said diverging walls to prevent other than arcuate movement between the plate and body; and securing means having its axis substantially in said main central plane to prevent said arcuate movement.

6. In a head for a golf iron the combination of a metal body having a channel laterally across the bottom thereof defined by arcuate and depthwise diverging sidewalls; a bottom plate, said body and bottom plate forming a blade having a main central plane, the top of said plate being substantially at right angles to said plane; pivoting means associating said plate in said channel of the body for relative arcuate movement; arcuately shaped and downwardly converging portions on the plate engaging with the diverging sidewalls to prevent other than arcuate movement; and securing means preventing said arcuate movement.

7. In a head for a golf iron the combination of a metal body having in the bottom thereof a non-circular recess with sidewalls, and having a channel laterally across the bottom thereof defined by arcuate and depthwise diverging sidewalls; a lie-determining bottom plate having in the top thereof a noncircular recess with sidewalls; pivoting means associating said plate in said channel of the body for relative arcuate movement; downwardly converging portions on the bottom plate engaging with said diverging sidewalls to prevent other than arcuate movement; a noncircular block; and a single screw associating the body and plate and maintaining said noncircular block snugly against the sidewalls of both recesses to prevent arcuate movement.

8. In a head for a golf iron the combination of a metal body having a channel laterally across the bottom thereof defined by depthwise diverging sidewalls; a bottom plate; downwardly converging portions on the plate, engageable with said diverging sidewalls; and securing means additionally securing the plate to the body.

9. In a head for a golf iron the combination of a metal body; a bottom plate; interengaging means on the body and plate including a channel having depthwise diverging sidewalls, and portions engaging said diverging sidewalls; positioning means locating the plate relative to the body with the bulk of the plate away from the body and directing the plate into accurate engagement with the body; and securing means maintaining the body and plate in engagement.

10. In a head for a golf iron, the combination of a main body; a bottom plate; pivoting means associating the plate and body for relative arcuate movement about an axis; interconnecting means on the body and plate, preventing other than arcuate movement therebetween; depthwise diverging side walls in said interconnecting means, said side walls being arcuately shaped relative to said axis; a main face in said interconnecting means, said main face intersecting said axis at right angles and combining with

said side walls to define a channel extending laterally across the head; portions in said interconnecting means interengaging with said side walls; and securing means adapted to prevent said

5 arcuate movement.

11. In a head for golf clubs, the combination of a metal body, with front and bottom faces, having a toe-to-heel length several times the face-to-back width, and having at least one 10 recess in the bottom face, with a main face of said recess at an appreciable angle to the bottom face and at substantially a right angle to the front face; and weighting means extending upwardly from the recess into the metal body with 15 the axis thereof substantially parallel the front face and at right angles to the main face of the recess.

12. In a head for a golf iron the combination of a metal body having in the bottom thereof a 20 noncircular recess with sidewalls and having a channel laterally across the bottom thereof defined by depthwise diverging sidewalls; a bottom plate having in the top thereof a noncircular recess with sidewalls; a noncircular block having an operative and inoperative position; downwardly converging portions on the bottom plate engaging said diverging sidewalls; and securing means associating the body and plate and normally maintaining the block in operative position 25 against the side walls of both of said recesses.

13. In a head for a golf iron the combination of a metal body having in the bottom thereof a noncircular recess with sidewalls and having a channel laterally across the bottom thereof defined by arcuate and depthwise diverging sidewalls; a bottom plate having in the top thereof a noncircular recess with sidewalls; arcuate and downwardly converging portions on the bottom plate engaging the side walls; pivoting means 35 associating the bottom plate in said channel of the body for relative arcuate movement; a noncircular block having an operative and inoperative position; and securing means associating the body and plate and normally maintaining the 40 block in operative position against the sidewalls of both of said recesses to prevent said arcuate movement.

14. In a head for a golf iron the combination of a metal body having in the bottom thereof a noncircular recess with sidewalls and having a channel laterally across the bottom thereof defined by arcuate and depthwise diverging sidewalls; a bottom plate having in the top thereof a noncircular recess with sidewalls, said bottom 55 plate and body forming a blade having a main central plane; pivoting means associating the plate in said channel of the body for relative arcuate movement about an axis substantially within said main central plane; arcuate and 60 downwardly converging portions on the bottom plate engaging with said sidewalls to prevent other than arcuate movement; a noncircular block having an operative and inoperative position and a single securing means associating the body and plate and normally maintaining the 65 block in operative position against the sidewalls of both of said recesses to prevent arcuate movement.

15. In a head for a golf iron the combination of a metal body having in the bottom thereof a noncircular recess with sidewalls and having a channel laterally across the bottom thereof defined by depthwise diverging sidewalls; a bottom 70 plate having in the top thereof a noncircular

recess with sidewalls, said bottom plate and body forming a blade having a main central plane; downwardly converging portions on the plate cooperating with said diverging sidewalls; a non-circular block having an operative and inoperative position; and a single securing means having its axis substantially in said main central plane and associating the body and plate and normally maintaining the block in operative position against the sidewalls of both of said recesses.

16. In a head for a golf iron the combination of a metal body having a channel laterally across the bottom thereof defined by arcuate and depth-

wise diverging sidewalls, said body having at least one weight-receiving recess; a bottom plate; pivoting means associating the plate in said channel of the body for relative arcuate movement including arcuate and downwardly converging portions on said bottom plate engaging with said diverging walls, said pivoting means preventing other than arcuate movement between the plate and body; securing means adapted to prevent said arcuate movement; and at least one weight locked in said weight-receiving recess by said bottom plate.

MILTON B. REACH.
